UNITED STATES PATENT OFFICE.

MELVIN N. LOVELL, OF ERIE, PENNSYLVANIA.

CLOTHES-WRINGER.

SPECIFICATION forming part of Letters Patent No. 253,537, dated February 14, 1882.

Application filed November 22, 1880. (No. model.)

To all whom it may concern:

Be it known that I, MELVIN N. LOVELL, a resident of Erie, county of Erie, and State of Pennsylvania, and a citizen of the United States, have invented new and useful Improvements in Clothes-Wringers; and I do hereby declare that the following is a full, clear, and exact description thereof, reference being had to the accompanying drawings and the letters 10 or figures of reference marked thereon.

My invention relates to clothes-wringers; and it consists in improvements in the construction and operation of the clothes-board, and in the arrangement of the springs in conjunction 15 with an intermediate bar of novel and peculiar form.

In the accompanying drawings my machine is illustrated as follows:

Figure 1 is a side elevation. Fig. 2 is an end 20 elevation. Fig. 3 is a transverse vertical section on the line $x-x$, Fig. 1.

The letters of reference indicate parts as follows:

A A B is the frame-work. C C are the rollers. D D are the clothes-guides, and form a part of the frame-work. E E are the clothes boards or aprons, upon which the clothes fall as they come from the rollers. F F are the clamps for attaching the wringer to the tub. F' 30 F' are the clamping-screws; f f, the bracket-irons, on which the swing-clamps F are pivoted and by which they are attached to the posts of the wringer. H H' are the tension-springs. G is a movable cross-bar, which operates in 35 connection with the springs. I is the screw for adjusting the tension of the springs. J J' are the journal-boxes of the rollers, and T represents the partition in the stationary tubs.

The construction of my machine is as follows:

40 The clamps F F are pivoted on the inside of the uprights A A of the frame-work, and may swing outwardly in either direction, so that the machine may be clamped to the tub either side front; or when used on a stationary wash-tub it may be clamped on either side of the division-board T.

45 The clothes-board E is fastened to castings E' E', which are pivoted to the standards A at e. When the machine is not in use and the 50 clamps F are folded up the clothes-board lies in a vertical position against the uprights, as

shown in Fig. 1 and also on the right of Fig. 2; but when the clamps are swung out, as shown on the left of Fig. 2, the clothes-board is raised so as to occupy a slanting position, as shown 55 on the left of Fig. 2, in which position it serves as an apron to direct the clothes as they come from the rolls. By duplicating these clothes-boards, placing one on each side of the machine, and also duplicating the guide-boards 60 D D, the machine is capable of admitting or discharging the clothes from either side. So, when in use on an ordinary tub, it is obvious 65 the crank can be made to come in place so as to be equally serviceable and convenient for either right-handed or left-handed persons. This feature is, however, more incidental than otherwise, the primary object of the construction being to adapt the machine for use on stationary wash-tubs.

70 In Fig. 2, T represents the division between two compartments of a stationary tub. The machine is there shown as in position for wringing the clothes that are in the compartment at the right of T, and letting them fall into the 75 compartment on the left. None of the drip-water will fall into the compartment on the left. It will all run directly down from the rolls into the right-hand compartment. The clothes will all fall upon the clothes-board, which is held 80 up by the clamps. We will suppose that the water in the right-hand compartment is the suds and that in the left-hand compartment is clear or rinsing water. As soon as the clothes are all out of the suds that water is drawn off 85 and the compartment is, we will suppose, filled with bluing-water, and the operator desires then to wring the clothes from the rinsing-water back into the right-hand compartment. To do this the wringer is unclamped and the clamps 90 are swung so as to extend from the other side of the machine, and the machine is then clamped upon the other side of the board T. The board E, which in Fig. 2 is shown as vertical, is brought into a sloping position, and the one 95 which is there shown as sloping drops to a vertical position. The work of wringing the clothes back into the right-hand compartment can then be proceeded with by turning the crank in an opposite direction.

100 The clothes-boards E E, when dropped down, form a continuation of the facing or guide

board D. The pivots on which they are hung are placed above the lower edge of the guide-boards. The object of this is that when the boards E are raised to serve as aprons their 5 upper and inner edges are taken away from the lower edge of the board D, and thus the drippings which run down the inside of the guide-boards cannot follow the under side of the aprons and drop into the compartment into 10 which the clothes fall after being run through the rollers. The dropping or pivoted clothes-board will be found advantageous on any form of wringer, whether used on one side or on both sides, as it gives an opportunity for having 15 a wide apron when in use; but when not in use, or when the machine is packed for shipping, it is out of the way and takes up no room.

There is nothing new in the construction of the clamps F F further than the position at 20 which they are attached to the uprights—viz., on the inner faces, and so that they can be thrown out in either direction, so as to attach the machine on either side of the division T without turning the machine around, and also 25 so that when folded they will lie between the folded clothes-boards, and when extended for use they serve as supports for the clothes-board which comes into use.

The construction and arrangement of the 30 springs and intermediate bar, and the operation and objects of the same, are as follows:

A single spring, having its ends bearing upon the movable journal-boxes of the upper roller or an interposed bar, and its middle bearing 35 on the cross-bar of the frame or on an adjusting-screw, is common. Such a spring is substantially the same as the lower spring, H, or the upper spring and a bar somewhat similar to that shown by me.

40 Reference is made to the patents to Phelps, No. 197,893, 1877, and Browning, No. 229,666, 1880; but neither of these contains nor in any way anticipates my invention, which in detail is as follows: A wringer having a single leaf-spring, to operate with safety to the spring, 45 will not have sufficient capacity between the rollers. I therefore employ two springs so applied as to produce the desired result.

I do not intend to claim as my invention the 50 simple duplication of the springs, (which is shown by Browning,) for such is not what I do alone to obtain the desired result.

H H' are the semi-elliptical springs. They are not of the same form, one, H, being shallower in its dish than the other, and hence 55 more pliable.

G is the intermediate bar before referred to. Its ends move in the slots in the uprights. The upper spring, H', rests its ends upon the 60 ends of the bar, and the lower spring, H, rests its apex upon the middle of the bar. The upper and lower sides of the bar are curved, but not alike. The curves differ because the forms of the springs differ. The object of this form

is to afford a bearing for the whole surface of the springs when they are strained to a certain degree of tension, and thereby arrest further tension of the spring, and thus avoid overstrain. Therefore the form of the bar G is a matter requiring special design, and is ascertained by knowing at what point the springs must be relieved of further tension. 70

When in operation the spring H, being so formed as to be most pliable, will first conform to the bar and be relieved, and afterward the 75 spring H'. The greatest pressure is required when the cloth passing between the rollers is thickest, and it will be seen that by my device this is accomplished without bringing this additional strain upon a spring which is already 80 under strain near its capacity, but by a spring lately brought into use or action. However, I do not wish to be limited to the use of springs of varying elasticity, for my bar G can be used 85 equally well with springs of equal elasticity. My bar G is intended to be so strong as to be non-elastic, or substantially so, for elasticity in that part would have no beneficial effect.

I am aware that it is not new to provide a 90 wringer with clamp-arms which are so pivoted as to swing either to one side or the other of the machine—as, for example, in the patent to Bogert, No. 134,633, January 7, 1873—and I do not therefore broadly claim such an arrangement of the clamps. 95

What I do claim is—

1. A clothes-wringer having an apron pivoted to swing below the guide-board, in combination with clamp-arms located and arranged as shown, whereby they can swing laterally 100 and automatically lift said apron and support it in an inclined position when the clamp-arms are in position for clamping, in the manner described.

2. A clothes-wringer having a gravity clothes-board, in combination with a clothes-guide located above the board, said board being pivoted above and to the rear of the lower edge of said guide, substantially as described, so that when the board has been raised into position for use its inner edge will be above the lower edge of the guide, for the purposes mentioned. 105

3. In a clothes-wringer having two semi-elliptical springs, the combination therewith of an intermediate movable bar having its upper and lower faces formed to conform to said springs when they are compressed to a certain degree of tension, substantially as and for the purposes described. 115

In testimony that I claim the foregoing I have hereunto set my hand this 17th day of November, 1880. 120

MELVIN N. LOVELL.
